Primary Examiner — Cynthia Underwood(74) *Attorney, Agent, or Firm* — Warner Norcross & Judd LLP(57) **CLAIM**

The ornamental design for line management device, as shown and described.

DESCRIPTION

FIG. 1 is a perspective view of a line management device of the present invention;

FIG. 2 is a top plan view of the line management device of FIG. 1;

FIG. 3 is a bottom plan view of the line management device of FIG. 1;

FIG. 4 is a right side view of the line management device of FIG. 1, which is a mirror image of the left side view; and,

FIG. 5 is a front elevation view of the line management device of FIG. 1 which is a mirror image of the rear elevation view.
